UNITED STATES PATENT OFFICE

2,499,034

DEICER HEAT DISTRIBUTING MEANS

Richard B. Park, West Hartford, Conn., assignor
to United Aircraft Corporation, East Hartford,
Conn., a corporation of Delaware

Application November 3, 1945, Serial No. 626,502

2 Claims. (Cl. 244—134)

1

This invention relates to heating devices for raising the temperature of selected portions of propeller blades to facilitate removal of ice coatings and to prevent the formation of ice coatings.

An object of the invention is the provision of a heater strip adhesively secured to the propeller blade.

Another object of the invention is the provision of a heater in which the heat is greatest along the leading edge portion of the blade and gradually diminishes chordwise of the blade toward the trailing edge.

A further object of the invention is the provision of electrically energized heating means for heating a metal strip which provides a gradation of the heating from the leading edge rearwardly of the blade.

Other objects and advantages will be apparent from the specification and claims and from the accompanying drawings which illustrate what is now considered to be a preferred embodiment of the invention.

In the drawings,

Fig. 1 is a side elevation showing the general arrangement of the blades, the de-icer strips and their source of electricity.

Fig. 2 is a side elevation of a blade with the de-icer strip applied.

Fig. 3 is a front elevation of the same blade.

Fig. 4 is an enlarged detail, with portions broken away of the interior of the leading edge strip before the rubber coating is applied.

Fig. 5 is a view taken along the lines Y—Y of Fig. 2.

Fig. 6 is a sectional view taken along the lines 6—6 of Fig. 2, and

Fig. 7 is an enlarged cross section of the blade leading edge with the heater strip applied.

The invention is shown as associated with a controllable pitch propeller having a hub 10 mounted on a shaft extending outwardly from an engine nose 12. Propeller blades 14 and 16 are supplied with metal leading edge portions 18 and 20 and have shank portions 22 and 24 extending into and rotatably supported by propeller hub 10. The metal leading edge strips 18 and 20 are electrically heated by electricity supplied from a generator having a stationary field portion 26 mounted on the engine nose and excited by a suitable source of electricity, such as a storage battery, and a rotatable armature portion 28 mounted on and rotatable with the propeller hub 10. Electricity is conducted from the armature 28 through slip rings 30 and 32 to heat-

2

ing wires on the inner surface of strips 18 and 20. For a more detailed description of the generator, reference may be had to U. S. application Serial No. 474,684, filed February 4, 1943, of Edwin D. Eaton, for Propeller anti-icer. Any other suitable source of electricity for heating the strips may, of course, be used in place of that specifically described above.

The blades, one of which, 14, is shown in Fig. 10 2, may be made of metal such as aluminum and retained in the hub by the usual thrust bearings 34. The shank ends of the blades are covered with a fairing 36 which may be expanded 15 rubber with a coating of neoprene 38. The blade 15 may be made of other materials than aluminum and the fairing may be made of the same material as the blade or other materials, but it is now preferred to apply a coating of neoprene or other suitable adhesive material to the blade at the 20 portions where it is desired to secure the heater strip.

The heater strip 18 is a metal sheet, preferably 25 aluminum, bent to conform to the leading edge portion of the blade. Heater wires 40, preferably insulated Nichrome, are supported on the inner surface of the aluminum sheet by small strips of aluminum 42 spot welded to the strip 18. The interior of strip 18, wires 40, and small supporting strips 42 are all coated with a layer of 30 rubber 46 or other insulating adhesive which will provide a surface which can be cemented to the neoprene or other coating 38. The coated assembly is then cemented or vulcanized onto the leading edge of the blade.

35 The heater wires 40 extend longitudinally of the strip 18 and are spaced transversely to cover a material transverse area but much less than the width of the strip 18 so that in effect they supply a concentrated heat source at the strip leading edge. The wires are shown as being threaded back and forth longitudinally of the strip 18 with the two ends of the wire secured to the aluminum strip and the center portion of the wire connected by one of the wires 44 to the generator. Heater wires 40 are, of course, insulated both from the aluminum strip 18 and the small holding strips 42 except where the heater wires are secured at their ends to the strip 18. One of the wires 44 connects the heater strip with one of the slip rings 30 and the other wire 44 connects the heater wire 40 with another of the slip rings 30.

40 The heater wires are thus embedded between the leading edge of the blade or its fairing and the strip 18. When the wires 40 are electrically

heated, they will heat the strip 18, with the greatest amount of heat concentrated at the leading edge portion. Strip 18 is constructed of good heat conducting material, such as aluminum, and the heat is, therefore, conducted throughout the strip, the quantity of heat and the temperature gradually diminishing from the leading edge rearwardly toward the side edges of strip 18. Such a construction is economical in that it will apply the greatest amount of heat where the greatest amount of heat is needed and gradually taper off that heat where less is required. The rubber coating 46 on the inside of the leading edge strip 18 serves as an insulating member and helps to prevent dissipation of heat into the blade and helps to confine the heat generated in the heater wires to the leading edge strip. If an adequate bond can be obtained, preferably by a cold cementing process, between the coating 46 and the blade or fairing material, the 20 coating 38 on the blade may be omitted.

It is to be understood that the invention is not limited to the specific embodiment herein illustrated and described, but may be used in other ways without departure from its spirit as defined by the following claims.

I claim:

1. In combination with a propeller blade, a heat conducting metal strip covering at least a portion of the leading edge of said propeller and extending rearwardly toward the blade trailing edge, a concentrated heat source located at and extending along the blade leading edge between said strip and said blade for supplying heat to a concentrated zone at the leading edge of said strip, said heat conducting metal strip distributing, by conduction rearwardly chordwise of said blade, heat supplied by said concentrated source to the leading edge of said strip so that the temperature is highest at the leading edge 40 and gradually reduces chordwise of said blade,

a layer of adhesive on the blade side of said metal strip and heat source, said adhesive securing said heat conducting metal strip to the leading edge portion of said blade and insulating said blade from heat radiated from said source.

5 2. In combination with a propeller blade, a sheet of heat conducting metal curved to conform to the shape of and covering at least a portion of, the leading edge portion of said blade and extending rearwardly therefrom, electric heating wires extending longitudinally along and concentrated at the leading edge portion of said conformed sheet to provide a concentrated heat source, means for securing said heating wires on the concave side of said heat conducting strip to supply heat in a concentrated zone at the sheet leading edge, said heat conducting sheet distributing said heat rearwardly chordwise of said blade by conduction through said sheet from said concentrated zone so that the greatest amount of heat is supplied to the sheet leading edge and gradually reduces chordwise of said blade, a layer of adhesive on the concave surface of said unformed sheet and over said wires, said adhesive securing said heat conducting sheet to said blade and insulating said blade from heat radiated from said heating wires.

RICHARD B. PARK.
